SHOE SOLE

Adolph L. Langenfeld, New Holstein, Wis., assignor to
A. L. Langenfeld, Inc., New Holstein, Wis., a corporation of Wisconsin

Application September 9, 1954, Serial No. 32,215

Term of patent 14 years

(Cl. D7—5)

Fig. 2.

Fig. 1.

Fig. 3.

To all whom it may concern:

Be it known that I, Adolph L. Langenfeld, a citizen of the United States, residing in New Holstein, in the county of Calumet and State of Wisconsin, have invented a new, original, and ornamental Design for a Shoe Sole, of which the following is a specification, reference being had to the accompanying drawing forming a part hereof.

Fig. 1 is a side view of a shoe sole embodying my new design;

Fig. 2 is a top view thereof;

Fig. 3 is a bottom view thereof; and

Fig. 4 is a rear end view thereof.

I claim:

The ornamental design for a shoe sole, substantially as shown.
